CLAIM

The ornamental design for a jewelry display stand, as shown and described.

DESCRIPTION

FIG. 1 is a front elevational view of a jewelry display stand showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a top perspective view thereof.

The appearance of the top surface of the horizontal trays not shown is identical to the appearance of the top surface of the trays shown in FIG. 3, and the appearance of the bottom surface of the trays not shown is identical to the appearance of the bottom surface of the trays shown in FIG. 4.
